HAROLD J. ROSENBERGER, OF BROOKLYN, NEW YORK, ASSIGNOR TO INTERNATIONAL COMMUNICATIONS LABORATORIES, INC., OF NEW YORK, N. Y., A CORPORATION OF NEW YORK

INTERPOLATING CIRCUIT FOR SUBMARINE CABLE OPERATION

Application filed March 28, 1931. Serial No. 526,104.

My invention relates to improvements in synchronous interpolating circuits for submarine cable operation.

The most serious drawback to the multiplex operation of a submarine cable is the fact that each letter in the standard multiplex code is five units in length as compared with the length of 3.7 units for the average letter in the cable Morse code. Since the speed of signalling over an ocean cable is mainly limited by attenuation which increases very rapidly with increase of signalling frequencies, it follows that the output that may be obtained with multiplex operation over an ocean cable is the ratio

$$\frac{3.7}{5}$$

of the normal cable code output.

However, as the multiplex five unit code is a two element code, it has been found possible to increase the speed of the multiplex operation over a cable until the unit signalling pulses are so attenuated as not to be received at the receiving terminal.

With such a method, it is theoretically possible to increase the signalling speed to the point at which the single unit pulses are entirely attenuated and the double unit pulses are the same length as the normal length of a single unit pulse.

In this case the normal signalling speed will be doubled so that the code used will have an equivalent length of 2.5 pulses per letter.

Thus the increase in speed over the normal cable code will be the ratio

$$\frac{3.7}{2.5}$$

The object of my invention is to provide a synchronous interpolating controlling circuit for supplying the missing single unit impulses lost by attenuation.

In my invention, I employ a vibrating tuning fork for timing the operation of the controlling or local circuit which supplies the missing single pulses.

Various details of my invention will be pointed out in the description to follow.

Referring to the drawing:

Fig. 1 shows in diagrammatic form the circuit and apparatus employed.

Fig. 2 shows the form of the signals transmitted into the cable.

Fig. 3 shows the form of the signals as received by the control circuit and apparatus, and

Fig. 4 shows the form of the signals from the output relay.

Referring to Fig. 1, signals from the cable 1 are received by the cable relay 50 through winding 2. When positive or spacing impulses pass through winding 2 from the cable, the tongue 3 is moved into engagement with the spacing contact 4. When negative or marking impulses are received, the tongue 3 moves into engagement with marking contact 5.

When no signals are being received, the tongue 3 remains in its mid-position, touching neither contact.

The positive signals are transmitted by closing contacts 80, which may represent the contacts of a key or sending device, and the negative impulses are transmitted by closing similar contacts 85.

The current source or battery supply for operating the apparatus and circuits of the receiving end of the cable comprises a single battery utilizing the two poles (positive and negative) instead of a divided battery of three poles (positive, negative and zero). The use of but a single battery of two poles permits a simpler circuit and less danger of short circuiting.

When no signals are being received (corresponding to the missing single unit pulse), the relay tongue 3 remains in its mid-position, touching neither contact. When positive pulses are received, a circuit is completed from positive battery through the tongue 3 and spacing contact 4 of the cable relay 50, through winding 9 of the receiving relay 60 to negative battery. This circuit energizes winding 9 which causes the tongue 30 to move to its spacing contact 32. When negative pulses are received, a circuit is completed from positive battery through the tongue 3 and marking contact 5 of the cable relay 50 through the winding 11 of the corrector re-

lay 55, through winding 10 of the receiving relay 60 to negative battery. This circuit energizes winding 10 which moves the tongue 30 to its marking contact 31 and also operates the corrector relay 55 in the standard manner for energizing and controlling the speed of the vibrating tuning fork 21, which vibrates at twice the line signalling frequency.

When the left-hand fork tine is moved to its contact 24 during the proper part of the fork oscillation, and a positive pulse is being received on the receiving relay, a circuit is then completed from positive battery through the left-hand fork tine, fork contact 24, tongue 30, spacing contact 32 of the receiving relay 60 through winding 33 of the auxiliary relay 65 to negative battery. This circuit energizes winding 33 which moves its tongue 35 to its spacing contact 37.

During the second half of the cycle of the tuning fork, the left-hand tine moves over and comes in contact with contact 23. At this time a circuit is completed from positive battery through the left-hand fork tine, contact 23, tongue 35, spacing contact 37 of the auxiliary relay 65, through winding 38 of the output relay 70 and also through winding 7 of the receiving relay 60. The current through receiving relay winding 7 energizes relay 60, tending to move its tongue 30 to its marking contact 31. If at this time the tongue 3 is still on its spacing contact 4 of the cable relay 50, the energization of winding 7 will not be able to overcome the effect of winding 9 so that the tongue 30 of the receiving relay 60 will still remain under control of the cable relay 50. If, on the other hand, the tongue 3 has moved away from its spacing contact 4 and is in its mid-position, there is no current in winding 9, and 7 is therefore effective and moves the tongue 30 to its marking contact 31.

When the cable relay 50 is moved to its marking contact 5, winding 10 of the receiving relay 60 is energized by a similar circuit as is described for winding 9, and the tongue 30 is moved to its marking contact 31. Subsequently the auxiliary relay tongue 35 is moved to its marking contact by a circuit through winding 34, and the output relay tongue 45 is moved to its marking contact 46 by a circuit through winding 39 in the same manner previously described. Also, a circuit is established through receiving relay winding 8 which tends to move its tongue 30 to its spacing contact 32. If the cable relay tongue 3 has moved off of its marking contact and is in mid-air, the current in winding 8 is effective to control the receiving relay tongue 30. But if the cable relay 50 is still on its marking contact, the energization of winding 8 is not effective and the tongue 30 remains on its marking contact 31. When no signals are received for a period of several unit pulses, the fork 21 and the auxiliary re-

lay 65 control the operation of the receiving relay 60, causing it to vibrate at the line frequency so that all the unit single pulses are filled in at the proper polarity.

Thus, the receiving relay 60 is always under control of the cable relay 50 when the tongue 3 of the cable relay is on either its marking or its spacing contact. During the times when the tongue 3 is in mid-position, the receiving relay 60 is controlled from the fork contact 23 and the tongue 35 of the auxiliary relay 65, so that the missing single pulses are correctly supplied by the local circuit of the fork.

Fig. 2 shows the signals as transmitted to the cable 1, and Fig. 3 shows the signals received by the cable relay 50, due to attenuation.

Fig. 4 shows the signals in the same form as the transmitted signals of Fig. 2, after they have been corrected and the missing single unit signals supplied.

What is claimed is:

1. A signalling system comprising means for receiving transmitted signals, and means including a single source of two pole current supply associated with said receiving means for supplying signals transmitted to but not received by said receiving means.

2. A signalling system comprising means for receiving transmitted signals, and means comprising a tuning fork and a single source of two pole current supply for supplying signals transmitted to but not received by said receiving means.

3. A signalling system comprising a relay for receiving transmitted signals, means comprising a tuning fork and an auxiliary relay operated thereby for controlling the operation of said receiving relay in case the transmitted impulses are not received by said receiving relay.

4. A signalling system comprising means for receiving transmitted signals, means comprising a tuning fork and a relay controlled thereby for supplying signals corresponding to signals transmitted to but not received by said receiving means.

5. A signalling system comprising means for receiving impulses transmitted at a certain frequency, means comprising a tuning fork vibrating at approximately twice the frequency of the transmitted impulses to supply impulses corresponding to the transmitted impulses which are transmitted to but not received by said receiving means.

6. A signalling system comprising a relay responsive to transmitted pulses, a second relay operated by said first relay when it responds, and means comprising a vibrating tuning fork for operating said second relay when the first said relay does not respond to said pulses.

7. A signalling system comprising a relay responsive to transmitted pulses, a second re-

lay operated by said first relay when it responds, and means including a single source of current supply for operating said second relay upon failure of said first relay to respond to said transmitted pulses.

8. A signalling system comprising an input relay responsive to transmitted pulses, an output relay for transmitting pulses corresponding to the pulses transmitted to said input relay, a tuning fork and an auxiliary relay, and means comprising said tuning fork and auxiliary relay for causing said output relay to transmit pulses corresponding to those transmitted to the input relay in case said input relay does not respond.

9. A signalling system comprising a receiving relay provided with a winding for the reception of marking signals and another winding for the reception of spacing signals for causing the operation of said relay, an auxiliary winding on said receiving relay for causing its operation in case no signals are received by said other windings.

10. A signalling system comprising a receiving relay provided with two independent windings for receiving signals to operate said relay, an auxiliary winding for said relay for causing its operation in case no signals are received by either of said other windings.

30. In witness whereof, I hereunto subscribe my name this 27th day of March 1931.

HAROLD J. ROSENBERGER.
